UNITED STATES PATENT OFFICE

165,500

HOMOGENIZER

Reinhard A. Yohpe, Battle Creek, Mich., assignor to Union Steam Pump Company, Battle Creek, Mich.

Application June 1, 1950, Serial No. 10,291

Term of patent 14 years

(Cl. D23—1)

To all whom it may concern:

Be it known that I, Reinhard A. Yohpe, a citizen of the United States, residing at Battle Creek, in the county of Calhoun and State of Michigan, have invented a new, original, and ornamental Design for Homogenizer, of which the following is a specification, reference being had to the accompanying drawing, forming a part hereof.

Fig. 1 is a side elevational view of a homogenizer, showing my new design, viewed from the left of Fig. 2.

Fig. 2 is a front elevational view, viewed from the right of Fig. 1.

Fig. 3 is a rear perspective view showing the

I claim:

The ornamental design for a homogenizer, as shown.

REINHARD A. YOHPE.
